CLAIM

The ornamental design for a pair of stabilizer arms for patient interface, as shown and described.

DESCRIPTION

FIG. 1 is a front perspective view of a pair of stabilizer arms for patient interface showing a first embodiment of our new design;

FIG. 2 is an enlarged portion of a portion of FIG. 1; FIG. 3 is enlarged portion of another portion of FIG. 1; FIG. 4 is a front perspective view of a pair of stabilizer arms for patient interface showing a second embodiment of our new design;

FIG. 5 is an enlarged portion of a portion of FIG. 4; and, FIG. 6 is enlarged portion of another portion of FIG. 4. The dot-dash broken lines illustrate the boundary lines of the enlarged portions of the pair of stabilizer arms for patient interface. The broken lines in the drawings illustrate portions of the pair of stabilizer arms for patient interface that form no part of the claimed design.
